CRYSTAL GRINDING MACHINE

John W. Moore, Velasco, Tex.

Application November 10, 1947, Serial No. 785,042

12 Claims. (Cl. 51—161)

1

This invention relates to a crystal grinding machine.

It is an object of the invention to provide a machine of the character described whereby watch crystals may be ground to an accurate transverse diameter so as to fit in the bezel of the watch case for which the crystal is being ground.

It is another object of the invention to provide a grinding machine of the character described which is equipped with gauges so mounted that the movement of the grinding jaws, relative to the crystal, will be stopped when the crystal has been precisely ground to fit said bezel.

While the grinder herein described has been specially designed for grinding watch crystals it is also adapted for general grinding purposes where it may be desired to grind a disc to a predetermined transverse diameter.

Other objects and advantages will be apparent from the following specification which is illustrated by the accompanying drawings, wherein—

Figure 1 is a side view of the grinder, partly in section, mounted on the lathe bed.

Figure 2 is a plan view.

Figure 3 is a cross-sectional view taken on the line 3—3 of Figure 1.

Figure 4 is a cross-sectional view taken on the line 4—4 of Figure 1, and

Figure 5 is a cross-sectional view taken on the line 5—5 of Figure 1.

Referring now more particularly to the drawings wherein like numerals of reference designate similar parts in each of the figures, the numeral 1 designates a stand to whose upper end a lathe bed 2 is secured in any preferred manner.

Mounted on one end of the bed 2 there are the upstanding aligned bearings 3, 4 in which a shaft 5 is mounted to rotate and fixed on this shaft between said bearings there is a series of driving pulleys 6 to receive a driving belt through which the shaft 5 may be driven.

Adjustably mounted on the other end of the bed 2 there is a tail stock 7 having an elongated bearing 8 therethrough to receive one end of the shaft 9 which is aligned with the shaft 5.

The outer end of the bearing 8 is enlarged in diameter and in said enlarged end there is a rod 10 whose outer end carries a hand grip 11 and whose inner end is formed with an enlarged head 12.

Between the head 12 and the opposing end of the shaft 9 there is a ball bearing 13.

Within the enlarged portion of the bearing 8 there is a coil spring 14 which surrounds the rod 59

2

10 and which is confined between the head 12 at one end and the cap 15 at the other end. This cap surrounds the rod 10 and is screwed onto the corresponding part of the tail stock 7.

The spring 14 is under compression so as to hold the ball bearing 13 against the adjacent end of the shaft 9.

The numeral 16 designates a watch crystal to be ground. It is held clamped between circular clamping jaws 17, 18, the former of which is fixed on the end of shaft 5 and the latter of which is fixed on the end of shaft 9. The crystal 16 is of conventional, concavo-convex shape and the adjacent sides of the jaws 17, 18 should be correspondingly shaped so as to fit the crystal and to grip it firmly between said jaws.

The bed 2 has a flat upper surface and mounted on said surface there is a channel shaped supporting frame having the horizontal base 19 and the upstanding side flanges 20, 21.

Depending from this frame and having a detachable connection therewith there is a rod 22 which extends through a suitable bearing in the lathe bed 2 and whose lower end is threaded to receive a clamp nut 23 whereby said frame may be clamped in fixed position relative to the bed.

Upstanding from the ends of the frame there are the transverse end flanges 24 and 25 and anchored to these flanges, one on each side, are the rods 26 and 27, which form tracks.

Located between the flanges 24 and 25 there is an upstanding adjustable, supporting plate 28 having the elongated sleeve-like bearings 29 and 30 secured thereto which are mounted on the respective corresponding rods 26, 27 so that the supporting plate 28 may be moved longitudinally with respect to said rods.

Fastened to the forward side of the plate 28 are the vertical guides, or tracks, 31, 32 which are spaced apart.

There are the similar upper and lower jaws 33, 34, preferably formed of suitable sheet metal and which diverge forwardly, as shown in Figure 1. They are of dovetailed formation, as indicated in Figure 4, and dovetailed into these jaws are the upper and lower abrasive elements 35, 36 formed of any selected material suitable for the purpose.

The inner end of the jaw 33 is turned upwardly and the inner end of the jaw 34 is turned downwardly, as indicated in dotted lines in Figure 1, and these overturned ends fit between the guides 31 and 32. These grinding, or abrasive, elements are partially enclosed by a semi-cylindrical hood 37, one end of which is suitably secured to the

upstanding plate 28 and whose forward end is free. This hood is provided with a transparent section 38 for inspection of the grinding operations.

Secured to the inner side of the hood 37 there is a bracket 39. Fastened to this bracket there is an arcuate leaf spring 40 whose ends are inwardly curved and bear against the jaws 33, 34 and are located forwardly of the overturned ends of said jaws so as to retain the jaws against detachment from the guide in which they move.

Around the shaft 5 and extending through and rotatable in the plate 28 there is a short tubular shaft 41. Fixed on the forward end of this shaft between the jaws 33, 34 there is a cam member 42. This member has the correspondingly pitched cam faces 43, 44.

Fixed to the other end of the tubular shaft 41 there is a handle 45 which is retained thereon by means of a nut 46. The handle 45 may be manipulated to turn the cam member 42 so that the cam faces 43, 44 will ride against the corresponding jaws 33, 34 to force them apart. On the rear side of the plate 28 there is an arcuate rack member 47 having spaced holes, or openings, 48 therein and pivotally mounted on the handle 45 there is a thumb lever 49. The lower end of this thumb lever 49 carries a dog 50 which may be engaged in either of the openings 48 and is retained in said engaged position by means of a flat spring 51 whose outer end is secured to the thumb lever 49 and whose inner end bears against the handle 45, as shown in Figure 1, so as to hold said dog in engagement in any selected opening 48.

By pressure on the thumb lever 49 the dog 50 may be released and said handle adjusted to any desired position so as to spread the jaws 33, 34 the desired distance apart depending on the diameter of the crystal being ground. When the handle 45 is released from the rack member 47 the spring 40 will force the jaws 33, 34 and the abrasive elements carried by said jaws inwardly toward each other.

The upper margin of the flange 21 is outwardly turned forming a table 52 whose upper side is formed with a dovetailed groove wherein the gauge plate 53 is mounted to slide. As shown the outer margin of the table is formed with a longitudinal depending flange 54.

Secured in any preferred manner to the upper side of the plate 53 there are the spaced strips of metal 55, 55 whose inner margins are beveled to form a dovetailed groove, as more accurately shown in Figure 5, and fitted into this groove and slidable therein there is a gauge strip 56 whose outer, or forward, end carries a grip member 57 whereby the gauge strip 56 may be moved longitudinally with respect to the gauge plate 53. The forward end of the gauge plate 53 is upwardly curved, as indicated in Figure 1, and is centrally slotted, as indicated in Figure 2, to allow the adjustment of the gauge strip 56. This gauge strip 56 is provided with an upstanding stop 58 at its inner end which may be secured thereto in any preferred manner. Secured to the forward end of the flange 54 there is a bracket 59 whose upper end is inwardly turned and extends over the gauge plate 53 and is spaced above it.

Threaded through the overturned end of the bracket 59 are the clamp screws 60, 60 which may be screwed downwardly into clamping relation with the strips 55 of said gauge plate to clamp the gauge plate against movement and

also threaded through the overturned end of the bracket 59 there is a clamp screw 61 in alignment with the gauge strip 56 and whereby said strip may be clamped against movement. When said screws 60, 61 are released the gauge plate 53 and the gauge strip 56 may be relatively adjusted, as desired, and when clamped by said screws held in said adjusted position.

Fixed to the forward end of the table 52 there is an internally threaded sleeve 62 through which the clamp screw 63 is threaded. This clamp screw may be screwed upwardly into clamping engagement with the gauge plate 53 to hold said plate against movement, or released, to permit the movement of the plate.

Secured to, and upstanding from, the gauge plate 53 there is a longitudinal bearing 64 which is internally threaded and threaded through this bearing 64 there is the screw gauge 65. The forward end of this screw gauge is extended and has a grip member 66 fixed thereon by means of which it may be turned. Also upstanding from the gauge plate 53 but slidable relative thereto, there is a fork 67 whose upper end is provided with spaced bearings 68 and 69 in which the extended end of the screw gauge 65 is rotatable and on said extended end between said bearings there is a stop 70 which prevents the longitudinal movement of the screw gauge 65, relative to the fork, as said screw gauge is turned. The fork 67 is provided with an outstanding stop 71 which is arranged opposite the stop 58, said stops 58 and 71 forming gauge points.

Fastened to the forward end of the bearing 64 there is another fork 72 whose lower end is forwardly turned and bifurcated, its fingers embracing the fork 67 to prevent said fork from turning.

Fastened to the rear side of the plate 28 there is a U-shaped stop 73 whose side arms are secured to said plate on opposite sides of the bearing 64 so that the stop 73 will be in alignment with the screw gauge 65.

In use the jaws 33, 34 should be adjusted to the proper distance apart depending on the diameter of the crystal 16 to be ground and the supporting plate 28 should then be moved forwardly until the margin of the unground crystal contacts with the abrasive elements 35, 36. The gauge plate 53 should then be moved rearwardly until the gauge screw 65 contacts the stop 73 and the screws 60 or 63 tightened to lock the gauge plate 53 in fixed position, and the gauge strip 56 should then be precisely adjusted so that the unground crystal 16 will fit snugly between the gauge points 58, 71 and the screw 65 then tightened to maintain such adjustment. The supporting plate 28 may then be returned to its original or starting position. The gauge screw 65 should then be turned until its rear end is in contact with the stop 73.

The unground crystal may then be removed from between the gauge points 58, 71 and a millimeter gauge should then be used to measure the exact diameter of the crystal seat of the bezel of the watch to which the crystal is to be fitted and the gauge point 71 should then be adjusted, by turning the gauge screw 65, until the gauge points 58, 71 are a distance apart equal to the diameter of the bezel seat, which is also the diameter of the crystal to be ground.

This adjustment will move the rear end of the screw gauge a distance from the stop 73 equal to the difference between the diameter of the un-

ground crystal and of the crystal after it is ground.

The unground crystal 16 may then be again clamped between the jaws 11 and 18 and the supporting plate 28 again moved forwardly by hand and the crystal will be ground as the plate moves forwardly until the stop 73 contacts the opposing end of the gauge screw 65 at which time the grinding operation will be completed and the crystal 16 will be of the same diameter as the bezel seat to receive it.

The drawings and description are illustrative merely while the broad principle of the invention will be defined by the appended claims.

What I claim is:

1. A crystal grinding machine comprising, a supporting base, a track thereon, an upstanding support mounted to move on said track, opposed jaws adjustable relative to each other on the support, opposed abrasive surfaces on the jaws, aligned shafts arranged axially with respect to the abrasive surfaces, clamp means on the shafts for gripping the crystal to be ground between them, said support and abrasive surfaces being movable to bring said surfaces into and out of contact with the crystal and means for rotating the shafts.

2. A crystal grinding machine comprising, a supporting base, a track thereon, an upstanding support mounted to move on said track, opposed jaws on the support radially adjustable toward and from each other, abrasive elements on the jaws, aligned shafts arranged axially with respect to said abrasive elements, clamp means on the adjacent ends of said shafts to clamp the crystal to be ground between them, said support being movable to bring the abrasive elements into and out of contact with the margin of the crystal, means for manually moving said jaws apart, yieldable means acting against the jaws and normally tending to move them toward each other.

3. A crystal grinding machine comprising, a supporting base, a track thereon, an upstanding support mounted to move on said track, opposed jaws on the support radially adjustable toward and from each other, abrasive elements on the jaws, aligned shafts arranged axially with respect to said abrasive elements, clamp means on the adjacent ends of said shafts to clamp the crystal to be ground between them, said support being movable to bring the abrasive elements into and out of contact with the margin of the crystal, means for manually moving said jaws apart, yieldable means acting against the jaws and normally tending to move them toward each other and means for maintaining the clamping jaws in yieldable contact with the crystal.

4. A crystal grinding machine comprising, a supporting base, a track thereon, an upstanding support mounted to move on said track, opposed forwardly diverging jaws adjustable relative to each other on the support, opposed abrasive surfaces on the jaws, aligned shafts arranged axially with respect to the abrasive surfaces, clamp means on the shafts for gripping the crystal to be ground between them, said support and abrasive surfaces being movable to bring said surfaces into and out of contact with the crystal and means for rotating the shafts.

5. A crystal grinding machine comprising, a supporting base, a track thereon, an upstanding support mounted to move on said track, opposed jaws on the support adjustable toward and from each other, abrasive elements on the jaws, aligned

shafts arranged axially with respect to said abrasive elements, clamping jaws on the adjacent ends of said shafts to clamp the crystal to be ground between them, said support being movable to bring the abrasive elements into and out of contact with the margin of the crystal, means for manually moving said jaws apart, means for maintaining the jaws at a selected point of adjustment, yieldable means acting against the jaws and normally tending to move them toward each other.

6. A crystal grinding machine comprising, a supporting base, a track thereon, an upstanding support mounted to move on said track, opposed forwardly diverging jaws on the support adjustable toward and from each other, abrasive elements on the jaws, aligned shafts arranged axially with respect to said abrasive elements, clamping jaws on the adjacent ends of said shafts to clamp the crystal to be ground between them, said support being movable to bring the abrasive elements into and out of contact with the margin of the crystal, means for manually moving said jaws apart, yieldable means acting against the jaws and normally tending to move them toward each other and means for maintaining the clamping jaws in yieldable contact with the crystal.

7. A crystal grinding machine comprising, a supporting base, a track thereon, an upstanding support mounted to move on said track, a guide on the support, opposed forwardly diverging jaws adjustable relative to each other along said guide, opposed abrasive elements on the jaws, aligned shafts arranged axially with respect to the abrasive elements, clamp means on the shafts for gripping the crystal to be ground between them, said support and abrasive elements being movable to bring said elements into and out of contact with the crystal and means for rotating the shafts.

8. A crystal grinding machine comprising, a supporting base, a track thereon, an upstanding support mounted to move on said track, opposed jaws on the support adjustable toward and from each other, forwardly diverging abrasive elements on the jaws, aligned shafts arranged axially with respect to said abrasive elements, clamping jaws on the adjacent ends of said shafts to clamp the crystal to be ground between them, said support being movable to bring the abrasive elements into and out of contact with the margin of the crystal, means for manually moving said jaws apart, means for maintaining said opposed jaws at a selected point of adjustment, yieldable means acting against the opposed jaws and normally tending to move them toward each other.

9. A crystal grinding machine comprising, a supporting base, a track thereon, an upstanding support mounted to move on said track, a guide on the support, opposed forwardly diverging jaws on the support adjustable along the guide toward and from each other, abrasive elements on the jaws, aligned shafts associated with the abrasive elements, clamping jaws on the adjacent ends of said shafts to clamp the crystal to be ground between them, said support being movable to bring the abrasive elements into and out of contact with the margin of the crystal, means for manually moving said diverging jaws apart, yieldable means acting against the diverging jaws and normally tending to move them toward each other and means for maintaining the clamping jaws in yieldable contact with the crystal.

10. A grinding machine comprising, a supporting base, rotatable clamp means yieldingly mounted above the base adapted to yieldingly grip the opposite sides of, and rotate, a disc to be ground, an upstanding support mounted on the base to move axially with respect to the clamped disc, forwardly diverging grinding jaws on the support movable, with the support, into contact with the margin of the unground disc and means on the base and support, respectively, arranged to contact, upon further movement of the support, to stop such forward movement of the support and jaws and thereby limit the reduction in transverse diameter of the disc being ground.

11. A grinding machine comprising, a supporting base, rotatable clamp jaws mounted above the base and spaced apart so as to clamp between them, and rotate, a disc to be ground, an upstanding support mounted on the base to move axially with respect to the clamped disc, forwardly diverging grinding jaws on the support movable, with the support, into contact with the margin of the unground disc and adjustable means on the base and support, respectively, arranged to contact, upon further forward movement of the support, to stop such forward movement of the support and jaws and thereby limit the reduction in transverse diameter of the disc being ground.

12. A grinding machine comprising, a supporting base, rotatable disc-like clamp jaws mounted above the base adapted to yieldingly clamp between them, and rotate, a disc to be ground, an upstanding support mounted on the base and manually movable axially with respect to the clamped disc, forwardly diverging grinding jaws on the support movable, with the support, into contact with the margin of the unground disc and adjustable means on the base and support, respectively, arranged to contact, upon further forward movement of the support, to stop such forward movement of the support and jaws and thereby limit the reduction in transverse diameter of the disc being ground.
